UNITED STATES PATENT OFFICE

148,511

DESIGN FOR A CORNER CHAIR

Roy Young, Wilmington, Calif.

Application September 21, 1946, Serial No. 133,483

Term of patent 14 years

(Cl. D15—11)

To all whom it may concern:

Be it known that I, Roy Young, a citizen of the United States, residing at Wilmington, in the county of Los Angeles and State of California, have invented a new, original, and ornamental Design for a Corner Chair, of which the following is a specification, reference being had to the accompanying drawing, forming part thereof.

I claim:

The ornamental design for a corner chair, as shown.

ROY YOUNG.
